UNITED STATES PATENT OFFICE.

FRANCISCO VERDAGUER, OF BALAGUER, SPAIN.

AEROPLANE.

Application filed December 5, 1922. Serial No. 605,108.

To all whom it may concern:

Be it known that I, FRANCISCO VERDAGUER, a subject of the King of Spain, and residing at Balaguer, Province of Lerida, 5 Spain, have invented certain new and useful Improvements in Aeroplanes, of which the following is a specification.

This invention relates to aeroplanes having front and back wings mounted on transverse axes on each side of the machine.

The object of the present invention is to provide mechanism whereby the wings are so interconnected as to effect an automatic balancing of the lifting forces on them, 15 while allowing the inclinations of the wings to be partly or wholly controlled by the pilot.

It has already been proposed to construct an aeroplane in which a divided front wing 20 and a back wing mounted on transverse axes were adapted to be moved by cables attached to a multiple-armed lever, an intermediate point of which was attached to a cord which was under the influence of a spring, whereby 25 the inclinations of the wings were automatically controlled.

The present invention consists in an improved aeroplane, in which front and back wings mounted on transverse axes on each 30 side of the machine are adapted to be moved by tie-rods attached to a steering plate which is mounted by means of a universal joint upon a tube whose position is adapted to be controlled by the pilot, whereby the 35 pilot may control the position of said tube so as to allow the inclinations imparted to the wings to be distributed automatically between all of the wings, or alternatively by directly acting upon the steering plate the 40 pilot may control the distribution of the lifting power between the wings.

In the preferred form of my invention the wings are combined with an elastically balanced steering wheel, inclinable and movable at the will of the pilot. According to the position assumed by the hand wheel the wings receive the requisite movement for aiding the manoeuvre which the aeroplane 45 is to execute.

Under those conditions the wings operate just as if they were rudders connected to the ends of the aeroplane fuselage and distributed symmetrically on each of its sides. Moreover the aeroplane is fitted for landing 50 purposes, with two front wheels and two back wheels. The front wheels can be

steered at the will of the pilot, and the back wheels are fitted with brakes so as to facilitate the movements of the aeroplane on the ground, and unable the pilot to steer the 60 aeroplane like a motor-car.

Furthermore, the improved aeroplane comprises a helm likewise steerable at the will of the pilot for facilitating the manoeuvres of the aeroplane.

One construction of an aeroplane comprising the improvements forming the subject of this invention is illustrated by way of example in the accompanying drawings in which:

Figure 1 is a plan of the improved aeroplane.

Figure 2 is a side view thereof.

Figure 3 is a front view thereof, and

Figure 4 is a longitudinal section on the 75 line IV—IV of Figure 1.

As shown, the improved aeroplane consists of the fuselage 22 which has the usual and suitable form and is fitted with an engine 26 and screw propeller 27 at its front part, and with another engine 26' and screw propeller 27' at its rear part. The improved aeroplane has four wings at its forepart, and four others at its rear part, arranged two and two on each side of the body. The 80 top front wings 1, 2 rock on an axle 41 arranged transversely at a suitable height above the supports 21 fixed to the fuselage. The lower wings 1', 2', rock on an axle 41' arranged in the lower part of the supports 21. The top wings are articulated to the lower ones by means of connecting rods 47 in such a manner that the movement executed by each top wing is exactly parallel to the movement executed by the corresponding lower wing, so that both wings have always the same angle of incidence at the same instant.

The lower axle 41' carries a lever 46 jointed to a tie-rod 45 attached to a bell-crank lever 51 whose other end is jointed by means of a pivot pin 40 (Fig. 4) to the tie-rod 30 which is screw-threaded at its upper end and is adjustable by means of a nut 23 bearing upon the steering wheel 24. The fixed supports 21 of the wings are suitably fastened to the fuselage by means of cables 37.

The upper and lower wings 3, 4, 3', 4' at the rear part are mounted in a similar manner; they rock on transverse axles 43, are supported by fixed supports 21'. The upper

wings are jointed to the lower wings by means of stanchions 48 at the points 44, and the lower wings carry a 'lever 46' which is jointed to the tie-rod 45'. The latter is 5 jointed in its turn to the bell-crank lever 51' which is pivoted by means of a pivot-pin 40' to the screw-threaded tie-rod 30' bearing upon the steering wheel 24 by means of a nut 23'. The fixed supports 21' are suitably attached 10 likewise to the fuselage by means of cables 37'.

The improved steering mechanism is shown in detail in Figure 4. It consists of the steering plate 24 suspended from the 15 upper tube 11 by means of a ball-and-socket joint 25 in such a manner that it can assume all suitable inclinations. The inner member of the ball-and-socket joint 25 is formed in one with a cup 25' which is 20 screwed to the upper tube 11 that slides inside the outer tube 15. The latter has an external screwthread on which screws a pulley 31 maintained in the part 22' of the fuselage by means of the ball bearings 12. 25 The cable 6, passing through the groove of the pulley 31, receives the steering movement in order that it may be situated at the hand of the pilot so that the latter, by operating the cable 6, is able to cause the pulley 30 31 to revolve in the proper direction for making the plate 24 rise or fall.

The cup 25' of the ball-and-socket joint 25 is suitably attached to the end of a spring 7 which bears at its opposite end 35 against the abutment 10 of the spindle 8 and is adjustable by means of the nut 8' which bears upon the closed end 15' of the tube 15. The inner tube 11 is also closed at its upper end 9, allowing only the passage 40 of the spindle 8, in order that, in the case of the spring 7 breaking, the abutment 10 shall bear against the closed end 9 of the tube 11, and the steering of the aeroplane shall not be wholly lost.

45 Upon the steering plate 24 there bear the nuts 23, 23' for adjusting the tie-rods 30-30' which transmit the movements of the front wings or to the back wings through the medium of the respective bell-crank levers 51, 51'. Moreover, the position 50 of the plate 24 is balanced by the springs 14 which are attached at one end to the thimbles 14' jointed to the base 16' of the central stem 16, and are attached at their 55 upper ends to the thimbles of the spindles 13, and are tensioned by means of the nuts 13' bearing upon the plate 24. The support 22' for this entire steering mechanism, forms 60 part of the fuselage of the aeroplane, and has stops 18 at suitable points for the purpose of preventing the steering of the aeroplane from getting out of hand in the case of the screwthreaded tube 15 having risen too high. Likewise this tube has stops 17 65 for preventing the plate 24 from losing its

position of control in the case where the tube 11 shall have risen too high, while, cables 19 are provided between the support 22' and the plate 24 for the purpose of preventing the plate 24 from dropping in the 70 case of the spring 7 having become damaged or when, by reason of a wrong manoeuvre, the wings have acquired a dangerous negative angle.

In order to facilitate the descent of the 75 aeroplane in those cases of damage, the stops 17 and 18 are arranged lower at the front part than at the rear, so that the aeroplane shall automatically descend with a planing movement, the stops being calculated to enable the wings to remain in the proper position.

The spring 7 acts equally upon all the wings at one time, and the springs 14 are intended to balance or compensate elastically the difference in the pressure or weight borne by each group of wings, for which purpose the tension of the springs is adjustable by means of the nuts 13'. Since the tie-rods 30, 30' are adjustable by means 90 of the nuts 23, 23', it will be perceived that the steering is elastic and adjustable in all its details.

If the speed diminishes much, the pressure underneath the wings will be smaller 95 than the force of the springs 7, and then the plate 24 will rise until it strikes the stops 17, and since the front stops are lower than the back stops, the steering plate will compel the wings to assume the slope corresponding to a planing descent. In the same manner the stops 18 will operate in the case where the tube 15 happens to rise excessively, thereby preventing in all cases the wings 100 from assuming a prejudicial angle.

In order to assure that the aeroplane shall work with the improvements forming the subject of this patent, the two engine groups 26, 26' are started; the aeroplane is released from the brakes, and it moves over the 110 ground; it is steered by means of the pedal 34, 35 until it has acquired the requisite speed for flight, at which moment the plate 24 is caused to rise by means of the pulley 31 which starts the transmissions to the levers 46, 46' of the front and back wings which are inclined in proportion to the distance traversed by the steering plate for flight, through a greater or smaller angle 115 of incidence as required, which depends on the weight, area and speed of the aeroplane, etc., wherefore the pilot will cease to rotate the pulley 31 at the instant when the desired impulse or ascent is attained.

120 Since it is desirable to get a perfect equilibrium of the aeroplane, the pilot, with his hard, moves the steering plate 24, thus producing equilibrium by inclining the said plate in the same sense as that which it is desired to impart to the aeroplane.

If the case should occur, when the aeroplane is flying normally that the plate 24 does not remain parallel to the pulley 34, this parallelism is obtained by means of the 5 nuts 23, and when once centralized, the same operation is effected with the nuts 13' and springs 14 for compensating elastically the unequal forces imparted by the rings to the plate 24.

10 If it be desired to turn to the right, the pilot, with his foot, pushes the bar 34—35 to the left, thereby bringing in the rudder 29 and the front wheels which latter are "filled" for this purpose; at the proper 15 time the plate 24 becomes inclined below the right-hand side. If it be desired to turn to the right in rising, it is necessary to incline the right-hand front side of the plate 24 upwards, and depress the rear of the 20 proper side. For turning to the left, the reverse movements are made.

Generally the pilot need not trouble about the losses of atmospheric equilibrium caused by the flexibility of the connection between 25 the wings and the steering plate 24, because if one wing experiences an abnormal push or depression, it transmits a corresponding movement to the opposite wing, thus restoring the equilibrium.

30 In order to increase the speed of the aeroplane, the general angles of incidence of the wings must be diminished, and the power of the engines must be increased, inasmuch as proof would be obtained of the contrary 35 at the cost of a descent; the reverse operations produce opposite effects.

To cause the aeroplane to rise, the power of the engine group and also the angle of the incidence of all the wings, are increased by 40 means of the pulley 31, the ascent being then checked by reference to the horizontal fuselage. The front edge of the plate 24 may also be inclined upwards, and the engine power be increased and the machine will 45 then rise with the fuselage inclined as in other machines. By executing the two operations there results a mixed inclination. In the descent the operations must be performed in the reverse direction.

50 For landing, the usual procedure can be adopted, but it is preferable to descend with the fuselage parallel with the ground and with the maximum amount of incidence of all the wings, which latter act in the case 55 of this invention, as a powerful brake, keeping the engine running at normal speed until the wheels take the ground. In this manner there is produced an extremely gentle tangential contact with facility of rising again, 60 in the case of the pilot observing unforeseen obstacles, because by keeping the engines running at full speed it is merely necessary to diminish the angle of incidence of the wings, in order to rise rapidly from the 65 ground.

As the aeroplane has come into contact with the ground with low velocity, the landing is effected slowly and, owing to the braking produced by the wings, it is sufficient to pull the lever of the back wheel brakes 70 to cause the aeroplane to stop as the result thereof.

Since the front wheels are capable of being steered any obstacles present on the ground can be avoided, and the pilot from 75 his seat can steer the aeroplane for travelling along a road or to the garage.

By removing the screws 50, all the wings are released for storage in a place of small 80 dimensions or for transport.

If desired, the center of gravity can be lowered in order to give more stability to the aeroplane without interfering with its working. No pendulating movement can occur through the distribution of weights and 85 points of support in the air such as by the arrangement of the wings, as well as the manner in which the points of support are distributed on the ground or on the wheels.

By the arrangement of the wings according to this invention, the usual great lengths of wings are dispensed with and the weights are distributed more uniformly; horizontal rudders, equilibrators, etc., are dispensed with; and the saving in weight and resistance to flight can be utilized to strengthen the others parts; this feature combined with the elastic suspension has the effect of greatly increasing the coefficient of safety at equal 90 weights.

The greater weight or greater moment of inertia corresponds at the fuselage of the aeroplane with the feature that the wings are light and are elastically articulated to the fuselage the wings yielding only to an abnormal thrust, with resulting smooth travel and suspension.

The effort required for handling the aeroplane is very small, because ball bearings can be provided at all the joints, so that the 110 wings are completely balanced by their being supported in the front third, and by each plane being connected to its opposite plane so as to produce counteracting forces upon the steering plate 24.

Since the forces acting upon the wings are balanced, and these all act like rudders it will be understood that the result is the maximum of obedience of the aeroplane with a minimum of effort.

The distance between the wings is very great, and the small displacement of the center to pressure which they can undoubtedly undergo, does not affect the stability of the aeroplane.

Any disturbance capable of influencing the flight of the aeroplane must be really of great magnitude, because the distribution of the masses gives a large moment of inertia 130 to the entire aeroplane, and because the

wings are light and yield readily to atmospheric influences the disturbances are compensated or damped by the springs, so that the pilot can easily remedy any occurring 5 disturbance.

The construction of the improved aeroplane achieves automatic stability. If an increase in pressure acts under the front wings, these will have a tendency to cause 10 the aeroplane to rise, but since they are connected to the steering mechanism, and the latter is elastic, then, if the disturbance is small, it will be damped, and if it is great, it will be transmitted through the medium 15 of the plate 24 which gives to the back wings a completely antagonistic movement with a tendency to cause the rear part of the aeroplane to rise, thus effecting a light and balanced ascent of the same.

20 If the increase of pressure acts under the front right wing and is small, it will be damped by the elastic transmission, and if it is great, by the pull of the plate 24, and since the connection of the back left wing 25 corresponds to the opposite equidistant point of the line passing through the center of suspension, there is a corresponding compensating action, and therefore, neither in this case nor in similar cases will the aeroplane 30 lose its equilibrium.

If the pressure is produced underneath all the wings, and the inertia of the aeroplane is great, the ends of the wings and the steering springs will yield, thus damping 35 the pressure without disturbing the equilibrium.

It is thus impossible for a breakage of the wings to occur by the action of the air, because the rear third of the wings is 40 flexible, and the connection between them and the body of the aeroplane is elastic, and they bear against strong steel axles.

Since the disturbances occurring during 45 the flight of the aeroplane are counteracted, the steering plate 24 can be left to itself for long periods in order to avoid fatigue or for giving attention to other objects, the steering being resumed when actual or intentional disturbances occur.

50 If the steering plate be let go, the engines having stopped, the aeroplane will lose each time more of its speed until a time when the thrust underneath the wings being small, the spring 7 will actuate the plate 24 until 55 the latter meets the stops 17 or 18 which give the proper inclination of the normal plane.

Since the change in the incidence takes 60 place only in the wings, the fuselage of the aeroplane will always be steerable in the direction of travel and therefore it will offer a minimum resistance to the advance and the screw propellers will give a maximum power output.

65 As the aeroplane maintains a horizontal

position, the sustaining planes are able to pass through extreme variations of incidence, and therefore it will be conceived that the maximum and minimum speeds of the aeroplane can be higher than in aeroplanes 70 with fixed wings, because there is a freedom from the danger of falling by reason of an exaggerated inclination of the fuselage of the aeroplanes, and because the proper plane is automatically re-established.

75 Since the transmissions are adjustable in full flight, and they can be combined with recording pressure gauges, the improved aeroplane is well adapted for very varied studies of angles of incidence in relation to the power, the resistance to flight and other factors.

80 It is impossible for the aeroplane to overturn, because the landings are tangential, the over-all height of the aeroplane is small, and the distance between the front and back wheels is great.

I claim:

1. In an aeroplane, a frame, front and rear transverse axles arranged on each side of said frame, forward and rear wings mounted for independent oscillation on said axles, an axially movable tube supported by the frame, means associated with said tube to permit the operator to axially move the 90 tube, a steering wheel mounted on said tube for universal movement, and means connecting said steering wheel with the wings for changing the inclination of said wings according to the movements of the steering 95 wheel.

2. In an aeroplane, a frame, front and rear transverse axles on each side of said frame, forward and rear wings mounted for independent oscillation on said axles, an axially movable tube supported by the frame, means to permit the operator to move the tube axially, a ball and socket joint carried by the tube, a steering wheel mounted on said joint so that it may be inclined in various directions, rods connected to said wheel, and links and levers connecting the rods to the wings, so as to transmit to each group of wings the movement corresponding to the movement of the steering 100 wheel.

3. In an aeroplane, a frame, front and rear transverse axles on each side of said frame, forward and rear wings mounted on said axles for independent oscillation, an axially movable tube, rotatable means for raising and lowering said tube, a ball carried by the tube, a steering wheel having a socket arranged around said ball, a spring suspending said tube, means for tensioning said spring, and means connecting the steering wheel to the wings to permit the wings to be controlled from said wheel.

4. In an aeroplane, a frame, transverse front and rear axles projecting from the op- 130

posite sides of said frame, right and left groups of front wings and right and left groups of rear wings mounted on said axles for independent oscillation, a steering wheel 5 capable of inclination and also capable of vertical movement, a system of rods and levers connecting said wheel with each one of the four groups of wings, a fixed support, four springs having their ends connected 10 to the fixed support and to the steering wheel, and means for adjusting the tension of said springs.

5. In an aeroplane having oscillating wings, a steering mechanism including an 15 outer threaded tube, a rotatable threaded pulley engaging the threads of said tube for raising and lowering the tube, means to permit the operator to rotate said pulley, an inner tube slidably mounted in the outer 20 tube, adjustable resilient means for suspending the inner tube within the outer tube, a universal joint carried by the tube, a steering wheel mounted on the universal joint, and means for connecting the steering wheel 25 to the wings of the plane.

6. In an aeroplane, a frame, front and rear transverse axles projecting from the opposite sides of said frame, forward right and left groups of wings and rear groups 30 of right and left wings mounted on the axles for independent oscillation, a steering wheel capable of being inclined in any sense and also capable of raising and lowering, means connecting the steering wheel 35 with the four groups of wings so as to impart to these latter the inclinations determined by the movement of the steering wheel, a series of stops for limiting the upward movement of the steering wheel, a 40 series of stops for limiting the downward movement of the wheel, said stops being arranged fore and aft and the forward stops being longer than the rear stops to permit the steering wheel to automatically steer the 45 plane in case of accident.

7. In airplanes the combination of a steering wheel mounted with a ball socket joint or center-piece, so as to be able to incline itself in any sense; this steering wheel 50 receiving the certain ends of the rods which

determine the motion of each group of front and rear wings, said rods resting on the steering wheel by means of nuts in order to be able to graduate at will the tension or effects of the rods.

55

8. In airplanes the improvement consisting in combining the steering wheel with springs, one for each group of wings, bearing at one of their ends against the lower plate of the post or column that sustains the 60 steering wheel and having at their upper end spindles which by means of nuts rest on the steering wheel, in order to be able to graduate at will the tension of the springs 65 as well as the equilibrium of the steering wheel and the wings.

9. In airplanes, the improvement consisting in fixing the center-piece which sustains the steering wheel to a tube slidable in the interior of another tube threaded on the outside, said last tube and the center-piece being linked or connected by means of a 70 spring which can be graduated at will.

10. In airplanes, the improvement consisting in applying as a nut for the threaded 75 tube which supports elastically the center-piece of the steering wheel, a pulley through the groove of which a cable runs, which is arranged so as to be near at hand for the pilot to be used, said pulley being mounted 80 in a bracket of the framework or body of the aeroplane, so that on turning the pulley, the outer tube and consequently the steering wheel rises and drops, motions which are transmitted to the corresponding wings. 85

11. In airplanes, the combination of the support which sustains the steering mechanism with stops which limit the ascent of the steering wheel, and the combination of the external tube with stops that limit the 90 descent of the steering wheel; the front-supports being lower than the rear-supports in order, for the sake of any average occurring, to cause the steering to lean against the indicated stops and the wings to take the suitable angle of incidence for the purpose of 95 automatically executing a gliding descent.

In testimony whereof I have signed my name to this specification.

FRANCISCO VERDAGUER.
